Patented Jan. 17, 1922.

Joseph A. Mariner Inventor
By his Attorney
A. Holleman Ward Jr.

UNITED STATES PATENT OFFICE.

JOSEPH A. MARINER, OF NEW YORK, N. Y.

HAIR-UNDULATING DEVICE.

1,403,512.

Specification of Letters Patent. Patented Jan. 17, 1922.

Application filed May 16, 1921. Serial No. 470,067.

To all whom it may concern:

Be it known that I, JOSEPH A. MARINER, a citizen of the United States, and a resident of the borough of Manhattan, in the county 5 and State of New York, have invented certain new and useful Improvements in Hair-Undulating Devices, of which the following is a specification.

My invention relates to hair-undulating 10 devices, and more particularly to a device of this character for producing Marcel waves in the hair, the device being of such character as to be readily handled by one dressing her own hair.

15 The objects of the invention are to provide a device of the character described which can be readily handled by the person whose hair is to be dressed, thus avoiding attendants, to provide a device on which 20 the hair may be wound from one end of the device in either direction about its axis so as to facilitate its use by inexperienced persons, and a device by means of which the entire tuft or bunch of hair to be heated 25 at one time will be given a decided "set" in a few minutes, thus saving time and increasing the permanency of the wave.

The invention consists in the novel features, arrangement and construction of the 30 parts hereinafter described in connection with the preferred embodiment of the invention, and the invention will be more particularly pointed out in the appended claims.

35 Further objects and advantages of the invention will more fully appear from the following description taken in connection with the accompanying drawings which, by way of example, illustrate two embodiments 40 of the invention.

Referring to the drawings, Fig. 1 is a side elevation of a device embodying the preferred form of the invention;

45 Figs. 2 and 3 are sectional views taken on lines 2-2 and 3-3 of Fig. 1;

Fig. 4 is a side elevation of a modification;

Fig. 5 is a sectional view of the same taken on line 5-5.

50 Referring to the drawings, 1 is a heat-able metal rod formed of any desired metal from which it may be preferable to make the device, but preferably of some metal such as aluminum or some of its alloys, 55 which may be readily molded in a two-piece mold, and is light and yet of high

heat conductivity. The rod is preferably tapered from one end to the other and is intended to be provided with a handle at the smaller end 2. The rod may be heated 60 in any desirable and well known manner such for example as by an electric heating coil into which the handle end may fit, or which may be located in the rod if it is partly hollowed out.

65 In the form of the invention shown in the drawings the rod is substantially flattened and is shown in section somewhat in the form of an ellipse so as to provide flattened surfaces 3, 3' and at its ends substantial ridges 4, 4' running longitudinally of the rod about which the hair is bent as it is wound around the rod. These longitudinal ridges or edges may be referred to as hair-undulating edges since the heating of the hair as it is wrapped over and around these edges causes a "set" or wave in the hair where it wraps over these edges.

70 In order to provide the rod with suitable guides for guiding the hair as it is wound about the rod, and also to enable the wound hair to be heated on three sides when wound upon the rod, I provide suitable projections 75 for this purpose.

75 It has been proposed to provide hair curling irons having projections, but these projections have either been in the form of a continuous sinusoidal projection or screw which permits the hair to be wound only in one direction around the iron from one end, 80 or else the iron and projections have been of such form that the hair is intended to be wound back and forth across the longitudinal member and around the alternate projections using them as pegs or fingers, 85 so to speak, around which the hair is wound. In the present invention the hair is intended to be wound around the tapering rod and the projections are so formed and positioned

90 as to be used as guides for the hair, and also to serve as heating elements for heating the side of the hair wound about the rod, so that substantial heating surfaces are presented on the sides as well as on the bottom of the hair wound about the rod. By 95 making individual projections as distinguished from a continuous sinusoidal or screw projection, it is possible to wind the hair in either direction about the rod from one end thereof, and at the same time to 100 obtain the desirable side heating surfaces. To accomplish these purposes the projec-

tions on one side of the rod are spaced apart and staggered with respect to those on the other side of the rod, and each projection is flattened so that they are wider than they are thick with the direction of their width extending transversely to the axis of the rod. Each projection also preferably has a ridge 6, 6' extending from the sides thereof and facing parallel to the axis 10 of the rod and extending from the base of the projection up to the top thereof. From these ridges 6 the surfaces of the projections taper to the end edges 7, so that each projection has a flattened side consisting 15 of two tapering surfaces 8 and 9. The projections are progressively spaced closer and closer together from the small end of the rod out to the large end because the tuft of hair will be thickest at the small end, 20 gradually reducing as it is wound out to the large end.

The greatest heating area is provided if the projections extend up from the flattened faces 3, 3', but if for certain uses of the 25 rod it may be desired to have the projections extend from the opposite edges of the rod instead of from the opposite flattened surfaces, then the device may be constructed as shown in Fig. 4 in which the rod 1' is of 30 the same shape as that shown in Fig. 1, and the projections 5' are of the same general character except that they project from the opposite edges of the tapered flattened rod instead of from the flattened side faces, and 35 are therefore not quite as wide from edge to edge as are the projections on the first form, but their flattened surfaces are of the same general shape in that they have the vertical edges facing parallel with the axis 40 of the rod, and have their sides tapering from these edges toward the ends of the projections.

The construction above described not only has the utility advantages set forth, but it 45 is of very pleasing appearance as a so-called toilet or hair dressing article, and its construction well adapts it to being molded in a two-part mold so that it may be readily drawn from the mold, due to the fact that 50 all of its parts taper from an axial plane respectively toward the top and bottom of the device, as to all surfaces.

In the use of the device, after it has been 55 heated either by a suitably located electric coil or otherwise, as is well understood, the handle (not shown) is then taken hold of and the end nearest the handle is held close to the scalp and the hair wound, either clockwise or anti-clockwise, as may be desired, around the rod in between the staggered projections which guide the hair in a sinusoidal path and at the same time serve, with the surface of the rod, as heating means for heating the hair, so that in a few moments the hair receives the desired "set," the

sharp edges or ridges presented facilitating this "set." The taper of the rod is to insure greater uniformity in the length of the waves. Since the tuft of hair is thickest at the roots, if the part of the rod receiving 70 this portion of the hair is of smaller diameter and the rod gradually tapers to the other end, it will result in more uniform waves.

While I have described my invention according to the present preferred embodiments thereof, it will be obvious to those skilled in the art, after understanding my invention, that various changes in the arrangement, form and construction of the parts may be made without departing from the spirit or scope of the invention, and I aim in the appended claims to cover all such modifications as come within the scope and spirit of my invention.

Having thus described my invention, what I claim as new and desire to secure by Letters Patent, is:

1. A device of the character described comprising in combination, a heatable metal 90 rod and a series of projections staggered along the longitudinal axis of the rod so as to provide therebetween paths around the rod along which hair may be wound in either direction from one end of the rod, said 95 projections being wider than they are thick and extending in the direction of their width transversely to the axis of the rod, so as to provide projections with substantial side surface areas against which the hair will 100 lie to heat the same when wound about the rod.

2. A device of the character described comprising in combination, a heatable metal rod tapering from one end to the other and 105 a series of projections staggered along the longitudinal axis of the rod so as to provide therebetween paths around the rod along which hair may be wound in either direction from one end of the rod, said 110 projections being wider than they are thick and extending in the direction of their width transversely to the axis of the rod, so as to provide projections with substantial side surface areas against which the hair will lie to heat 115 the same when wound about the rod.

3. A device of the character described having in combination, a heatable metal rod tapering from one end to the other and having hair-undulating ridges extending 120 longitudinally thereof on opposite sides, and a series of projections staggered along the longitudinal axis of the rod so as to provide therebetween paths around the rod along which the hair may be wound in 125 either direction from one end of the rod, said projections being wider than they are thick and extending in the direction of their width transversely to the axis of the rod, so as to provide projections with substan- 130

tial side surface areas against which the hair will lie to heat same when wound about the rod.

4. A device of the character described having in combination, a heatable metal rod tapered from one end to the other and substantially flattened and having longitudinal hair-undulating ridges on opposite sides thereof, and a series of projections from the opposed flattened surfaces staggered one set with respect to the other along the longitudinal axis of the rod, said projections being wider than they are thick and extending in the direction of their width transversely 15 of the axis of the rod.

5. A device of the character described having in combination, a heatable metal rod tapered from one end to the other and substantially flattened and having longitudinal hair-undulating ridges on opposite sides thereof, and a series of projections from the opposed flattened surfaces staggered one set with respect to the other along the longitudinal axis of the rod, said projections being wider than they are thick and extending in the direction of their width transversely of the axis of the rod, said projections being tapered in the direction of their width toward each end to form end edges.

6. A device of the character described having in combination, a heatable metal rod and a series of independent projections spaced longitudinally along one side of the rod, the projections being flattened and in 35 the direction of their greatest diameter extending transversely of the rod, the projec-

tions being so positioned as to permit the hair being wound around the rod in between them so as to bring the sides of the hair so wound into engagement with the flattened surfaces of the projection. 40

7. A device of the character described having in combination, a heatable metal flattened rod, a series of independent projections spaced longitudinally along one side 45 of the rod and a series of independent projections spaced longitudinally along the other side of the rod, the projections being flattened and in the direction of their greatest diameter extending transversely of the 50 rod, the rod being of materially greater sectional dimensions than that of the projections.

8. A device of the character described having in combination, a heatable flattened 55 metal rod tapering from one end to the other, a series of independent projections extending from one flattened surface of the rod and spaced longitudinally along the rod, and a series of independent projections from 60 the opposite flattened face of the rod spaced along the rod, said projections being so positioned on the rod as to permit hair to be wound around the rod therebetween in either direction from one end of the rod, and the 65 projections being so shaped as to present substantial heating side surfaces facing one another so that the hair is effectively heated on three sides as it is wound about the rod.

In testimony whereof, I have signed my 70 name to this specification.

JOSEPH A. MARINER.
